ELECTRICAL CONNECTER

Francois C. Bradley, Union, Miss.

Application July 30, 1932, Serial No. 627,029

5 Claims. (Cl. 173—360)

This invention relates to an electrical connector and has relation more particularly to a connector of this kind adapted to be used in connection with an electric light bulb, attachment plug, fuse plug and the like, and it is primarily an object of the invention to provide a connector which may be readily and conveniently slipped in a screw threaded socket and effectively retained therein.

10 Another object of the invention is to provide a connector of this kind constructed in a manner whereby after it has been properly engaged within a desired socket it will effectively resist withdrawal from the socket.

15 The invention consists in the details of construction and in the combination and arrangement of the several parts of my improved electrical connector whereby certain important advantages are attained and the device rendered simpler, less expensive and otherwise more convenient and advantageous for use, as will be hereinafter more fully set forth.

The novel features of my invention will hereinafter be definitely claimed.

20 In order that my invention may be the better understood, I will now proceed to describe the same with reference to the accompanying drawing, wherein:—

25 Figure 1 is an elevational view illustrating an electrical connector constructed in accordance with an embodiment of my invention and in applied position.

Figure 2 is a view similar to Figure 1 but of the connector alone in quarter turn relation;

30 Figure 3 is a sectional view taken substantially on the line 3—3 of Figure 1 with the screw shell omitted;

Figure 4 is a view similar to Figure 3 but showing certain of the parts in a second position;

35 Figure 5 is a view in plan of the blank from which the bow spring and its parts are produced.

As illustrated in the accompanying drawing my invention is disclosed as being employed in connection with a conventional electric bulb B, although it is to be understood that it can be employed in other ways, as for example as a conventional plug for electrical equipment. My improved device as herein illustrated comprises a base or shell 1 associated with the bulb B in a conventional manner and which has its periphery substantially smooth and unobstructed except for an annular groove 2 extending circumferentially therearound adjacent to its outer end. The base of this groove 2 at substantially diametrically opposed points is provided with the

relatively large slots 4 and at a point substantially midway of the slots 4 with an additional smaller slot 5.

Arranged within the base or shell 1 is a flat bow spring 6 of desired tension and which has struck out from its opposite end portions hook-like lugs 7, said lugs being disposed in the same general direction circumferentially of the base or shell. The spring 6 midway its ends is provided with an outstanding pin 8 which works within the slot 5. The hook-like lugs 7 are spaced apart a distance whereby when the pin 8 is at one end of the slot 5 said hook-like lugs 7 will be free to move in and out with respect to the base or shell 1 through the slots 4 so that the base or shell 1 may be readily and conveniently slipped within internally threaded sockets.

The outer portions of these hook-like lugs 7 are formed to readily engage within the thread of the socket member whereby the base or shell 1 may be effectively applied and engaged within the socket member yet without the necessity of turning or screwing the base or shell 1 into the socket member. Before the base or shell 1 is inserted within a socket member the spring 6 is adjusted into a position as illustrated in Figure 4 to bring the hook-like lugs 7 in position to freely move inwardly through the slots 4 as the member or shell 1 is forced by direct thrust within the socket member.

The base or shell 1 is insertible within an internally threaded socket member by direct thrust and after the base or shell 1 has been initially inserted within the socket member by giving the same a slight turn in one direction, as to the right, and to an extent allowed by the length of the slot 5, the free end portions of the hook-like lugs will be caused to overlie portions of the base or shell 1 whereby said lugs are held against inward movement thus resisting withdrawal of the base or shell from within its socket. Upon reverse turning movement of the applied base or shell 1 the same of course can be readily removed.

The pin 8 by its coaction with the edges of the base or shell 1 defining the slot 5 provides means whereby the spring 6 is held against undue lateral movement and thus maintaining the spring in substantially a fixed path of travel in a direction circumferentially of the base or shell 1. This pin 8 also coacts with the end edges of the slot 5 to limit the extent of movement of the spring 6 with respect to the base or shell 1 in a direction circumferentially of said base or shell 1.

From the foregoing description it is thought to be obvious that an electrical connector construct-

ed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation 10 of the several parts herein shown in carrying out my invention in practice except as herein-after claimed.

I claim:-

1. As a new article of manufacture, an electrical connector comprising a shell for insertion within an internally threaded socket member, said shell having circumferentially spaced openings, and a bow spring positioned within the shell and having lugs normally extending outwardly 20 of the shell through said openings, said lugs when extended having engagement with the thread of the socket member, said shell and bow spring having limited relative rotary movement, the lugs being hook-shaped to overlap the shell upon relative movement of the spring and shell in one direction to hold the lugs against movement inwardly of the shell, and means carried by the spring between the lugs and coacting with the shell for maintaining the spring in a substantially fixed path of travel.
2. As a new article of manufacture, an electrical connector comprising a shell for insertion within an internally threaded socket member, said shell having circumferentially spaced openings, a bow spring movably positioned within the shell and having lugs normally extending outwardly of the shell through said openings, said lugs when extended having engagement with the thread of the socket member, said shell and bow spring having limited relative rotary movement, the lugs being hook-shaped to overlap the shell upon relative movement of the spring and shell in one direction to hold the lugs against movement inwardly of the shell, said shell having a slot in its wall in which said part interengages to provide means for holding the spring in substantially a fixed path of travel.
3. As a new article of manufacture, an electrical connector comprising a shell for insertion within an internally threaded socket member, said

shell having circumferentially spaced openings, a bow spring movably positioned within the shell and having lugs normally extending outwardly of the shell through said openings, said lugs when extended having engagement with the thread of the socket member, said shell and bow spring having limited relative rotary movement, the lugs being hook-shaped to overlap the shell upon relative movement of the spring and shell in one direction to hold the lugs against movement inwardly of the shell, and means carried by the spring between the lugs and coacting with the shell for maintaining the spring in a substantially fixed path of travel.

4. As a new article of manufacture, an electrical connector comprising a shell for insertion within an internally threaded socket member, said shell having circumferentially spaced openings, and a bow spring movably positioned within the shell and having lugs normally extending outwardly of the shell through said openings, said lugs when extended having engagement with the thread of the socket member, said shell and bow spring having limited relative rotary movement, the lugs being hook-shaped to overlap the shell upon relative movement of the spring and shell in one direction to hold the lugs against movement inwardly of the shell, said spring between the lugs having an outstanding part, the shell having a slot in its wall in which said part interengages to provide means for holding the spring in substantially a fixed path of travel.

5. As a new article of manufacture, an electrical connector comprising a shell having circumferentially spaced openings, and a bow spring positioned around the shell, said spring having lugs normally extending through the openings in the shell, said lugs being adapted to engage with the threads of a threaded member, said shell and bow spring having limited relative rotary movement, the lugs being hook-shaped to overlap the shell upon relative movement of the spring and shell in one direction and to hold the lugs against lateral movement.

FRANCOIS C. BRADLEY,
